UNITED STATES PATENT OFFICE.

EMIL NEUGEBAUER, OF WIESBADEN, GERMANY.

SIPHON.

No. 923,879.

Specification of Letters Patent.

Patented June 8, 1909.

Application filed January 8, 1909. Serial No. 471,286.

To all whom it may concern:

Be it known that I, EMIL NEUGEBAUER, a subject of the German Emperor, and residing at 2 Schillerstrasse, Wiesbaden, Germany, have invented certain new and useful Improvements in Siphons, of which the following is a specification.

This invention relates to improvements in siphons and the objects of my improvement are to provide an automatic siphon, that is to say a siphon which will become charged and will start automatically by the mere immersion of part of said siphon into a vessel containing liquid which it is desired to cause to flow out of said vessel over the edge of said vessel in the manner of an ordinary siphon. I attain these objects by constructing the improved siphon with an inlet portion and an outlet portion, the inlet portion constituting a short siphon and the outlet portion constituting a large siphon, the two portions or siphons being connected in series by joining the outlet leg of the short siphon by a bend with the inlet leg of the long siphon, the top of the short siphon being situated at a lower level than the top of the long siphon, and the inlet of the short siphon being situated at a higher level than the outlet of the long siphon.

In the accompanying drawings:—Figure 1 is a side elevation, partly in vertical section of the improved siphon and Fig. 2 is a view showing the improved siphon in side elevation on a smaller scale in operation for emptying liquid from a tank into a receptacle, both the latter being shown in vertical section.

The improved siphon comprises what may be considered to be an ordinary siphon, *c*, *a*, *b*, bent round at the lower end, *b*, of its short leg and continued upwardly to form what may be considered also to be an ordinary siphon, *b*, *d*, *e*, shorter than the first mentioned ordinary siphon, that is to say, the top, *d*, of the siphon, *b*, *d*, *e*, is situated at a lower level than the top, *a*, of the siphon, *c*, *a*, *b*.

In operation, the improved siphon, *c*, *a*, *b*, *d*, *e*, is placed in the tank, *g*, to be emptied, with its portion, *b*, *d*, *e*, immersed in the liquid in the tank as shown in Fig. 2 so that the lower top, *d*, of the siphon is situated beneath the level of the liquid in the tank. The

lower end, *c*, of the long leg, *a*, *c*, of the improved siphon is situated below the bottom of the tank, *g*, and dips into a vessel, *f*, which receives the discharge of the siphon. As soon as the improved siphon is immersed as described the liquid in the tank, *g*, enters the end, *e*, of the shorter siphon, *e*, *d*, *b*, as indicated by the arrow, and thus causes the said shorter siphon to come into operation. By this means the liquid flows down in the leg, *d*, *b*, and flows up in the leg, *b*, *a* as indicated by the arrows with an impetus such that its momentum will carry it over the bend, *a*, into the long leg, *a*, *c*, of the siphon thereby charging and starting the whole siphon automatically and thus causing a steady siphoning of the liquid from the tank, *g*, into the vessel, *f*.

Having now described my invention what I claim as new and desire to secure by Letters Patent is:—

1. In siphonic apparatus the combination of two siphons of equal diameters connected together in series by a continuous duct having the same common diameter as the said siphons, the top of the first siphon being situated at a lower level than the top of the second siphon, and the inlet of the short leg of said first siphon being situated at a higher level than the outlet of the long leg of said second siphon, whereby the said apparatus constitutes a self-charging and self-starting siphon on immersion of said first siphon into the liquid to be siphoned over.

2. In a siphon the combination of a longer siphon, a shorter siphon and a bend connecting the inlet leg of the longer siphon with the outlet leg of the short siphon, whereby on immersion of the shorter siphon in liquid, the combined siphon will charge itself automatically and will start automatically to discharge the liquid by siphonic action, as set forth.

3. In a siphon, the combination of a long leg, a short leg, and an inverted siphon portion connected at one end with a bend to the top of said long leg, and at its other end with a bend to the top of said short leg, the bend at the top of the long leg being situated at a higher level than the bend at the top of the short leg, whereby the siphon is rendered self-charging and self starting by immersion of the short leg in the liquid to be siphoned over, as set forth.

4. A siphon in which the shorter leg is bent up at its lower end and continued to a point situated at a lower level than the top of the bend of the long leg of the siphon, where it is
5 bent down again to form the inlet leg of the siphon whereby the siphon is rendered self-charging and self starting as set forth.

In testimony whereof I have signed my name to this specification in the presence of two subscribing witnesses.

EMIL NEUGEBAUER.
